COLLECTOR ASSEMBLY

William C. Wiley, Detroit, Mich., assignor to Bendix Aviation Corporation, Detroit, Mich., a corporation of Delaware

Application July 9, 1951, Serial No. 235,744

8 Claims. (Cl. 250—41.9)

This invention relates to mass spectrometers and more particularly to a new collector assembly for mass spectrometers. The invention also relates to a method of collecting ions in a mass spectrometer.

Mass spectrometers are known in which ions of different mass are initially subjected to a field of substantially constant force by an ion source such that the ions of relatively light mass attain a greater speed than the ions of heavier mass. The ions are then directed into a magnetic field of substantially uniform intensity in a direction perpendicular to that of the magnetic field. This field causes the ions to describe a substantially circular path, preferably in a substantially horizontal plane. After a predetermined number of complete revolutions, the ions are collected and the time required for them to describe the predetermined number of revolutions is measured. Since the relatively light ions travel faster than the heavier ions, the time required for the ions to complete their travel gives an indication of their masses.

In order for the ions to describe a complete number of revolutions, the ion collector must be located directly below or above the ion source. This prevents the ion collector from being as large as might be desired and causes only the ions describing an optimum path to actually reach the collector. Since a large number of ions are lost between the ion source and the ion collector, the strength of the measurements of the time required for the ions of different mass to reach the collector assembly is reduced, with a corresponding reduction in the accuracy of the measurements. Further inaccuracies are produced because some of the ions not describing an optimum path travel through a number of revolutions different from the predetermined number and thus reach the collector assembly at a different time than the other ions of corresponding mass.

This invention provides a mass spectrometer having an ion collector so disposed that the ions are collected after they rotate through a predetermined angle which is less than a complete revolution. The ion collector is also disposed to collect substantially all of the ions after they have travelled through the predetermined angular distance from the ion source. By so disposing the ion collector, strong and accurate measurements of the time required for the ions to travel through the angular distance are obtained.

An object of this invention is to provide a mass spectrometer having an ion collector for collecting the ions travelling through the mass spectrometer after they have travelled through a predetermined angular distance different from an integral number of revolutions.

Another object is to provide a mass spectrometer of the above character having an ion collector for collecting the ions travelling through the spectrometer after they have travelled through a predetermined angular distance constituting less than a complete revolution.

A further object is to provide a mass spectrometer of the above character having an ion collector for collecting substantially all of the ions travelling through the mass spectrometer.

Still another object is to provide a mass spectrometer of the above character for providing strong and accurate indications of the time required for the ions to travel through a predetermined angular distance.

2

A still further object is to provide a method for collecting all of the ions travelling through a mass spectrometer after they have described a predetermined angle less than a complete revolution.

5 Other objects and advantages will be apparent from a detailed description of the invention and from the appended drawings and claims.

In the drawings:

10 Figure 1 is a perspective view illustrating the disposition of a mass spectrometer relative to a magnet for creating a magnetic field in the spectrometer;

15 Figure 2 is a perspective view of the mass spectrometer shown in Figure 1, illustrating the appearance and relative disposition of an ion source and an ion collector in the spectrometer;

20 Figure 3 is a perspective view illustrating in detail the ion source shown in Figure 2.

25 Figure 4 is a perspective view illustrating in detail the ion collector shown in Figure 2 and also showing in block form the measuring equipment associated with the collector; and

30 Figure 5 is a diagrammatic view illustrating the travel paths of different ions.

35 In one embodiment of the invention, a permanent magnet, generally indicated at 10, is provided with a yoke 12 and oppositely disposed pole pieces 14 and 16 vertically separated from each other by an air gap. The magnet is adapted to supply a magnetic field of substantially uniform strength across the air gap. A mass spectrometer, generally indicated at 18, is located in the air gap between the pole pieces 14 and 16 and has oppositely disposed cylindrical faces of a cover 20 pressing against the horizontal surfaces of the pole pieces 14 and 16. An ion source, generally indicated at 22, and an ion collector, generally indicated at 24, are suitably housed within the cover 20, which is evacuated to a relatively low pressure.

40 The ion source 22 includes a horizontally disposed filament 26 made from a suitable material, such as tungsten, and negatively biased with respect to ground by a battery 59. The filament is supported by a pair of leads which extend from terminals 28 suitably secured to the cover 20. A grounded shield 30 having an inverted U-shape and a relatively narrow slot 32 in the horizontal leg of the U is suitably supported by the cover 45 20 to substantially enclose the filament 26. The horizontal leg of the shield 30 supports a receptacle 34 having a horizontally disposed slot aligned with the slot 32 and a relatively narrow slot 36 in one of its vertical walls.

45 50 A plate 38 having a relatively narrow slot 40 aligned with a slot 36 is mechanically connected as by brackets to the receptacle 34 in insulated relationship to the receptacle and is electrically connected to a conventional pulse forming circuit 42, adapted to supply pulses having a negative voltage relative to ground. A conduit 44 extends from an external container (not shown) through an opening in one of the vertical walls in the receptacle 34. The container is adapted to hold molecules of the different gases constituting an unknown mixture and to feed molecules of such gases into the mass spectrometer 18 for analysis as to their masses or as to their relative abundance.

55 60 The ion collector 24 includes a shield 48 supported as by brackets 50 within the cover 20 and a receptacle 52 supported as by brackets 54 within the shield 48 in insulated relationship to the shield. The shield 48 is grounded, and a relatively low positive voltage, such as 20 volts, is applied on the receptacle 52 by a battery 60 to collect secondary electrons emitted from the receptacle when ions impinge on it. The shield 48 and receptacle 52 are rectangular parallelepipeds, with corresponding sides of each parallelepiped being parallel to one another. Each paral-

lelepiped is open at the side facing the flow of ions but the open side of the receptacle 52 is slightly recessed within the shield 48. A grounded screen grid 56 extends across the open side of the shield 48 and also covers the open side of the receptacle because of the recessed nature of the receptacle. The open side of the shield 48 is slightly smaller in area than the area formed in the spectrometer by the plane through which the open side extends. Similarly, the open side of the receptacle 52 is slightly smaller in area than the open side of the shield 48. The sides of the shield and receptacle parallel to the open sides extend from a position adjacent the ion source 22 at a predetermined angle to the direction in which the ions are emitted from the source. Thus, the ions rotate through a predetermined angle, such as 315°, before they strike the side of the receptacle 52 parallel to the open side, as will be explained in detail hereafter. A time indicator, such as an oscilloscope 58, is connected to the receptacle 52 to indicate the relative times at which the ions of different mass impinge upon the receptacle 52. The oscilloscope 58 is connected to receive voltage pulses from the pulse forming circuit 42 for initiating the horizontal sweep of the oscilloscope at substantially the same time negative pulses are applied to the plate 38.

In operation, electrons are emitted from the filament 26 when the filament is sufficiently heated by an electrical current passing through it. These electrons are attracted upwardly through the slot 32 in the bottom of the shield 30 because of the negative bias on the filament 26 with respect to the grounded receptacle 34. As the electrons move through the confined space within the receptacle 34, they strike molecules of gas which flow from the container (not shown) through the conduit 44 and into the receptacle as a result of the difference in pressure between the container and the mass spectrometer. The molecules of gas which flow into the mass spectrometer include the different gases in the unknown mixture stored within the container and have a predetermined abundance ratio to the gases in the container.

As a result of the collision between electrons and gas molecules, some of the molecules become ionized into electrons and positive ions. The ions are attracted towards the plate 38 when a voltage pulse of negative polarity is applied on the plate 38, and these ions are emitted through the slot 40 in the plate 38 and the slot 36 in the receptacle 34. The voltage pulse on the plate 38 is cut off before the ions reach the plate so as to apply an equal force on all of the ions. Because of the narrowness of the slots 36 and 40 and the alignment of the slots, the ions are emitted in a direction substantially perpendicular to the plane of the slots. Since the voltage on the plate 38 causes it to attract all of the ions with equal force, the ions of relatively light mass attain a greater velocity than the ions of heavier mass before they pass through the slot 36 in the receptacle 34. All of the ions pass in a relatively sharp pulse through the slot 36 because of the negative voltage pulse applied on the plate 38.

The ions are also emitted in a direction substantially perpendicular to the magnetic flux lines formed between the pole pieces 14 and 16, since the flux lines lie in substantially the same plane as the slots 36 and 40. This causes the magnetic field to exert a force upon the ions in a direction perpendicular to both the direction of the magnetic field and the direction of ion travel, such that the ions adopt a circular path. However, the ions of light mass rotate through their circular orbit faster than the ions of heavy mass since the angular velocity of the ions is inversely proportional to their mass. This may be seen from the relationship

$$\frac{d\theta}{dt} = \frac{eH}{m}$$

where

H =the strength of the magnetic field;

m =the mass of an ion;

e =the electrical charge on the ion; and

$\frac{d\theta}{dt}$ =the angular velocity of the ion.

The above equation is derived on pages 280 and 281 of "Principles of Electricity" by Page and Adams (1931 edition).

Because of their relatively great angular velocity, the ions of relatively light mass reach the receptacle 52 before the ions of heavy mass and produce a charge upon the receptacle when they impinge on it. Any secondary emission which takes place when ions impinge on the receptacle 52 is collected back at the receptacle because of the difference in voltage between the receptacle and the shield 48 and the electrical and mechanical sheltering action provided by the receptacle. Thus, by measuring the charges appearing on the receptacle 52 and the times at which the charges appear, an indication can be obtained by the indicator 58 of the masses of the different gases in the unknown mixture and the relative abundance of each gas.

The mass spectrometer disclosed above has several important advantages. Because of the relative displacement between the ion source 22 and the ion collector 24, the ion collector is able to occupy substantially all of the transverse area perpendicular to the direction of the ion flow. As a result, practically all of the ions travelling in a circular orbit through the mass spectrometer are collected by the receptacle 52, since the receptacle 52 is almost as big as the shield 48 within which it is contained. By collecting substantially all of the ions which describe a circular path in the mass spectrometer, the receptacle 52 produces strong and positive signals which give a clear indication of the time required for the ions of different mass to reach the receptacle.

The signals from the ion collector 24 are also sharply defined because of the fact that all of the ions of a particular mass are collected at the same time. This simultaneous collection of all of the ions of a particular mass occurs even though the ion collector 24 is located at a particular angle relative to the direction of ion emission, as illustrated in Figure 2. As discussed previously, if the ions of all masses describe a circular path of similar radius—for example, the path 60 illustrated in Figure 5—the ions of light mass will reach the collector before the ions of heavy mass because of the relatively great angular velocity imparted to them by the action of the magnetic field.

It may happen, however, that some ions of a particular mass may be ejected into the magnetic field in the mass spectrometer at a slower speed than other ions of the same mass. Since the centripetal force exerted upon the ions is inversely proportional to the speed of the ions as well as directly proportional to their mass, the ions having a speed below the average for their mass travel through a path, such as the path 62, having a smaller radius than the path 60. The relatively short length of the path 60 as compared to the length of the path 62 compensates for the slow speed of the ions describing this path and causes the ions describing this path to rotate through a predetermined angular arc, such as 315°, in substantially the same time as the other ions of the same mass.

In like manner, ions of a particular path having a speed greater than the average speed for ions of that mass may describe a path, such as the path 64, having a greater radius than the path 60 and may rotate through a predetermined angular distance in the same time as required for the other ions of the same mass. Thus, by disposing the ion collector 24 relative to the ion source 22 so that the ions rotate through a predetermined angle, such as 315°, before impinging on the ion collector, all of the ions of a particular mass are collected at the same time, regardless of their speed. The collection of all ions having a particular mass also occurs at the same instant since all of the ions rotate through the same angular distance, which is less than one com-

plete revolution. Collecting all of the ions before one complete revolution prevents some of the ions from rotating through a different number of revolutions than other ions of the same mass and minimizes any blurring in the measurements that are obtained.

The magnetic force applied on the ions should be fairly large in order to apply a relatively great centripetal force on the ions and to make the diameter of the cylindrical cover 20 defining the outer dimensions of the mass spectrometer relatively small. The magnetic force should also be fairly large so that the ions can move at a relatively high speed and still describe a circular path of reasonable diameter. Fast movement of the ions minimizes the deflecting action produced by stray fields, either electrostatic or electromagnetic, and reduces any blurring that may take place. Since the strength of the magnetic field produced by the magnet 10 is inversely proportional to the length of the gap between the pole pieces 14 and 16, it is desirable to keep the gap as small as possible. This is effectuated by removing the ion collector 24 from a position directly below the ion source 22 and by disposing it at a predetermined angle relative to the source. In this way, the size of the mass spectrometer is considerably reduced and its cost as well.

Other ion sources, such as the source disclosed and claimed in co-pending application, Serial No. 221,554, filed April 18, 1951 by Ian H. McLaren and me, now Pat. No. 2,732,500, may be used as the source 22. In addition, other ion collectors, such as a scintillation counter or electron multiplier, may be used as the collector 24 as long as they are disposed in the mass spectrometer in a manner similar to that disclosed above.

Although this invention has been disclosed and illustrated with reference to particular applications, the principles involved are susceptible of numerous other applications which will be apparent to persons skilled in the art. The invention is, therefore, to be limited only as indicated by the scope of the appended claims.

What is claimed is:

1. A mass spectrometer, including, means for emitting ions in pulses in a particular direction, means for subjecting the ions to a magnetic field providing lines of flux in a direction substantially perpendicular to the direction of ion emission so as to produce a rotation of the ions, means for collecting the ions upon their rotation through a substantially constant angular distance different from an integral number of revolutions, the collecting means being disposed in substantially the same direction as the magnetic field and at an angle to the emitting means to receive the ions after their angular rotation and means for measuring the times of flight of the ions to determine their masses.

2. A mass spectrometer, including, means for providing magnetic lines of flux in a particular direction, means for emitting ions in pulses in a direction perpendicular to the magnetic lines of flux so as to produce a substantially circular travel path for the ions, means for collecting the ions after their revolution through a substantially constant angular distance less than one revolution, the collecting means being disposed in substantially the same direction as the magnetic lines of flux and at an angle to the emitting means to receive the ions after their angular rotation, and means for measuring the time required for the ions of different mass to rotate through the substantially constant angular distance.

3. A mass spectrometer, including, an ion source for emitting ions in pulses in a particular direction, magnetic means operative on the ions in a direction substantially perpendicular to the direction of ion emission to produce a rotation of the ions, a collector assembly disposed with a plane for receiving the ions in substantially parallel relationship to the plane of emission of the ions from the ion source and in substantially perpendicular relationship to the direction of ion travel, the receiving plane of the collector being disposed in intersecting relationship to the emitting plane of the ion source to

collect the ions after their rotation through a partial revolution, and means for measuring the time required for the ions to reach the collector assembly.

5 4. A mass spectrometer, including, an ion source for emitting ions in pulses in a particular direction, magnetic means operative on the ions in a direction substantially perpendicular to the particular direction to produce a rotation of the ions, a collector assembly disposed in substantially the particular direction and in intersecting relationship to the ion source to collect the ions after they have rotated through a fraction of a complete revolution, and means for measuring the time required for the ions to reach the collector assembly.

15 5. A mass spectrometer, including, an ion source operative to emit ions in pulses in a substantially horizontal plane, means magnetically operative on the ions to provide for the ions a circular travel path in the horizontal plane, a collector assembly extending from the ion source at substantially a fixed angle relative to the source and in perpendicular relationship to the direction of ion travel and covering substantially the full horizontal and vertical lengths of the spectrometer in directions substantially perpendicular to the direction of ion travel to collect the ions after their rotation through a partial revolution, and means for measuring the times at which the ions reach the collector assembly.

20 6. A mass spectrometer, including, a cover having an axis in a first direction, an ion source disposed within the cover in the first direction to emit ions in pulses in a direction substantially perpendicular to the first direction, magnetic means for producing a magnetic field in substantially the first direction to produce a rotation of the ions, a collector extending from the ion source in the first direction and across the space within the cover to collect substantially all of the ions after their rotation through a substantially constant angle constituting a partial revolution, and means for indicating the relative times at which the ions of different mass are collected.

25 7. A mass spectrometer, including, a magnet having a pair of pole pieces separated from each other by a suitable gap and adapted to produce across the gap a magnetic field having a substantially uniform density, a cover disposed within the gap and having an axis substantially parallel to the magnetic field, an ion source disposed within the cover in the direction of the axis to provide pulses of ions in a direction substantially perpendicular to the magnetic field, an ion collector disposed within the cover adjacent the ion source in the direction of the axis and extending across the space within the cover to collect substantially all of the ions after their rotation through a partial revolution, and means for indicating the relative times at which the ions of different mass are collected.

30 8. A mass spectrometer, including, a magnet having a pair of pole pieces separated by a suitable air gap and adapted to produce across the gap a magnetic flux having a substantially uniform density, a cylindrical cover disposed within the gap with its axis substantially parallel to the magnetic field, an ion source for emitting pulses of ions in a direction substantially perpendicular to the direction of the magnetic flux, an ion collector positioned within the cover relative to the ion source to collect all of the ions in each pulse after their rotation through a substantially constant angle less than a complete revolution, and means for indicating the relative times at which the ions of different mass are collected.
